[57] CLAIM

The ornamental design for a manifold connector, as shown and described.

DESCRIPTION

FIG. 1 is a top side elevational perspective view of a manifold connector made in accordance with the present invention;

FIG. 2 is a bottom side elevational perspective view of the manifold connector of FIG. 1;

FIG. 3 is a top view of the manifold connector of FIG. 1;

FIG. 4 is a bottom view of the manifold connector of FIG. 1;

FIG. 5 is a side view of the manifold connector of FIG. 1, the opposite side view being identical; and,

FIG. 6 is a second side view of the manifold connector of FIG. 1, the view offset approximately 90 degrees from FIG. 5, the opposite side view being identical.

FIG. 1

FIG. 2

FIG. 3

FIG. 4

FIG. 5

FIG. 6
